GUN

Walter T. Gorton, Springfield, Mass.

Application April 2, 1942, Serial No. 437,371

12 Claims. (Cl. 42—76)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to guns and more particularly to the barrel thereof. A gun barrel is subjected to severe conditions in normal operation and the reaction of the interior surfaces of the chamber and bore of the barrel to these conditions is generally the determining factor of the operating life of the gun. Both the chamber and the bore of a gun barrel are subject to corrosion, which is the term generally applied to deterioration of these interior surfaces by the formation of oxides and chlorides of iron. Such corrosion is caused by the liberation of very active chemicals, particularly oxygen, in the discharge of each cartridge, and takes place despite careful cleaning. In addition the barrel bore is also subjected to a deteriorating effect known as erosion. The exact reason for erosion is a subject of many conflicting theories but it is apparently caused by the high velocity washing of the steel surface by high temperature and high pressure gases developed by the discharge of the cartridge. The effect of corrosion is the pitting and rusting of the steel surfaces of the chamber and barrel. The effect of erosion appears as an actual washing away of portions of the bore surface.

The resultant detrimental effects of corrosion and erosion on the performance of a gun are well known. The corrosion of the chamber is particularly detrimental to the operation of a gun of the automatic type. In such type of gun, ease of extraction of the empty cartridge case is a prime factor; however, the roughening of the chamber surface by erosion makes the extraction gradually more difficult until the necessary extracting force exceeds that which the automatic mechanism of the gun can develop. Hence the gun fails to operate. The corrosion and erosion of the bore produces an enlargement of bore diameter thus permitting the gases to blow by the projectile, resulting in a gradually increasing loss of muzzle velocity of the projectile. Furthermore the deterioration of the lands of the rifling causes inaccurate grooves to be cut in the projectile resulting in a loss of accuracy and the malfunction known as "key-holing" of the bullet.

It has been previously suggested, as in U. S. Patent No. 1,886,218 to Olin and Schuricht, that corrosion and erosion of the bore of gun barrels might be retarded by the electrolytic deposition of a coating of chromium throughout the entire bore. It is an object of this invention to apply this suggestion in a novel manner to protect the chamber and bore of a gun from corrosion and erosion. It is an object of this invention to provide a coating of hard and practically non-corrosive metal to the chamber and the portion of the bore immediately adjacent to the chamber

whereby the actual physical configuration of the interior of the bore is changed.

It is a further object of this invention to apply a coating of hard and practically non-corrosive metal to a portion of a gun barrel bore whereby retardation of corrosive and erosive effects is obtained and at the same time a substantial increase in the muzzle velocity of the projectile is secured.

10 A particular object of this invention is to obtain an increase of muzzle velocity of the projectile by an electroplated deposit of a hard metal on a portion of the bore.

15 The specific nature of the invention as well as other objects and advantages thereof will clearly appear from a description of a preferred embodiment as shown in the accompanying drawing in which:

20 Fig. 1 is a sectional view of a gun barrel embodying this invention.

Fig. 2 is an enlarged sectional view of the chamber end of a gun barrel embodying one modification of this invention.

25 Fig. 3 is also an enlarged sectional view of the chamber end of a gun barrel embodying another modification of this invention.

In Fig. 1, there is shown a gun barrel 1 having a bore portion 2 and a cartridge chamber 3. The barrel is rifled in any conventional manner, providing it with the lands 4. It has been observed that in a firearm of the automatic type, corrosion of the barrel chamber is a more serious detrimental factor to the performance of a gun than corrosion of the bore, due to the difficulty of extraction. It has been further observed that practically all serious erosion effects are produced in the vicinity of the barrel chamber and the portion of the bore immediately adjacent to the chamber. It follows that if only these

30 portions were provided with a coating of hard and practically non-corrosive metal, the detrimental effects of corrosion and erosion of gun performance will be substantially reduced. At the same time the cost of a coating of such limited extent will be only a fractional part of the cost of a coating extending throughout the bore. A coating 5 of a suitably hard, corrosion resisting metal having good adhering properties is provided covering the chamber and the adjacent part of the

35 bore. While chromium has been found to be a particularly desirable coating metal, it is obvious that other metals having similar properties may be utilized for example, nickel, cadmium, or silver. The thickness of this coating may preferably be only a few ten-thousandths of an inch which is well within the range of standard tolerances permitted today in interior dimensions of the barrel and bore of the gun. It is, therefore, not necessary to provide a gun with a non-standard chamber or bore dimension or a special diameter cartridge or projectile. Of course thicker

40 45 50 55 60

coatings may be applied if the gun dimensions are modified accordingly.

As shown in Figure 2, in exaggerated non-proportional relation, the coating 5 may be of uniform thickness throughout the chamber and the adjacent portion of the bore and then tapers down to a negligible thickness as shown at 5a; or as shown in Figure 3, a coating 5 may be applied such that the thickness of the coating gradually decreases throughout its entire length, that is, from the chamber into the bore. Limited advantages may be obtained by applying a tapered deposit to the bore alone. This procedure may be desirably used when the gun barrel does not integrally include a chamber. The distance to which the coating should be extended into the bore is not critical but it is imperative that the coating does not extend throughout the entire length of the barrel. In a preferred modification, the coating should extend over about one-third of the length of the bore. The minimum length of coating of the bore should be such as to protect that portion of the bore immediately adjacent to the chamber which is subject to the most severe erosive action.

Such coating is preferably produced by electroplating methods but it should be understood that the method of producing the coating is immaterial to the practice of the invention so long as a securely bonded coating of the described dimensions is produced.

A gun provided with one of the platings described not only has greatly increased resistance to corrosion and erosion but also has a substantial increase in muzzle velocity of the projectile as compared with an unplated gun of the same bore dimensions. The explanation for the substantial increase is not entirely clear but several factors are believed to contribute to its production. The most important factors are believed to depend on the slight constriction produced in the bore by the coating. The effect of this constriction is twofold; first, the available clearance through which the gases may blow by the projectile is reduced thus producing higher pressure; secondly, the grooves produced in the projectile by the plated lands 4 will be of slightly greater depth than necessary for the passage of the projectile along the unplated portion of the lands 4. In effect, the projectile is sized by the plated portion, then eased out into the unplated portion of the bore by the taper 5a of the plating 5 and then more or less "floats" out through the remainder of the bore. The leakage of gases through the increased clearance between the projectile and the unplated portion of the bore is not a serious factor in this portion of the bore since the gas pressure is substantially reduced. At any rate there would appear to be a substantial reduction of frictional resistance to the movement of the projectile while traversing the unplated portion of the bore. There is also less frictional resistance to the movement of the projectile in the plated portion of the bore due to the lower coefficient of friction of the plating metal. The slight constriction of the bore produced by the plating does not necessarily tend to increase projectile friction because the projectile is plastic under the applied pressure and upsets to fill the bore and rifling grooves.

It is to be noted that the increase in velocity obtained by plating the rear portion of the bore is not only substantially greater than can be obtained by an unplated bore having the same dimensional constriction characteristics but it is

also substantially greater than that obtained by a bore plated its entire length.

Apart from the retardation of corrosion and erosion which is inherent in a plating of metal such as chromium, the life of the bore is further prolonged by the fact that the plating 5 protects that portion of the lands 4 which does the initial work of swaging grooves into the projectile, hence reducing wear on such portion.

I claim:

1. A gun barrel having a chamber and a bore and a metallic coating covering the chamber and the adjacent portion of the bore, said coating tapering to a negligible thickness within the bore.

2. A gun barrel having a chamber and a bore and a metallic coating covering the chamber and the adjacent portion of the bore, said coating having a uniform thickness throughout the chamber and tapering to a negligible thickness within the bore.

3. A gun barrel having a chamber and a bore and a tapered depth metallic coating covering the chamber and the adjacent portion of the bore, said coating decreasing to a negligible thickness within the bore.

4. A gun barrel having a chamber and a bore and a hard, corrosion-resistant, metallic plating applied to the chamber and the adjacent one third of the bore, said plating tapering to a negligible thickness along the bore.

5. A gun barrel having a chamber and a bore and an electroplated deposit of chromium covering the chamber and the adjacent portion of the bore, said plating tapering to a negligible thickness within the bore.

6. A gun barrel having a chamber and a bore and an electroplated deposit of chromium covering the chamber and the adjacent portion of the bore, said plating having a uniform thickness throughout the chamber and tapering to a negligible thickness within the bore.

7. A gun barrel having a chamber and a bore and a tapered depth electroplated deposit of chromium applied to the chamber and the adjacent portion of the bore, said plating decreasing to a negligible thickness within the bore.

8. A gun barrel having a corrosion-resistant, metallic coating covering the breech end of the bore, said coating tapering to negligible thickness within the bore.

9. A gun barrel having an electroplated deposit of chromium covering the breech end of the bore, said plating tapering to a negligible thickness within the bore.

10. A gun barrel having a chamber and a bore and a metallic coating covering a substantial portion of the bore which extends from a point adjacent the chamber to a point within the bore and being arranged whereby the bore is relatively constricted throughout the coated portion as contrasted with its muzzle end.

11. A gun barrel having a chamber and a bore and a metallic coating substantially covering the chamber and the adjacent portion of the bore, said coating ending within the bore and being arranged to constrict said coated portion of the bore relative to its remaining portion.

12. A gun barrel having a chamber and a bore and an electroplated deposit of chromium substantially covering the chamber and the adjacent portion of the bore, said plating ending within the bore and arranged whereby said plated portion of the bore is relatively constricted as contrasted with its unplated portion.
